UNITED STATES PATENT OFFICE.

MARY GRIFFIN HEBERLY, OF SPRINGVILLE, NEW YORK.

PROTECTOR FOR TELEPHONE-MOUTHPIECES.

1,214,459.

Specification of Letters Patent. Patented Jan. 30, 1917.

Application filed April 20, 1916. Serial No. 92,360.

To all whom it may concern:

Be it known that I, MARY GRIFFIN HEBERLY, a citizen of the United States, residing at Springville, in the county of Erie 5 and State of New York, have invented new and useful Improvements in Protectors for Telephone-Mouthpieces, of which the following is a specification.

This invention relates to a protector which 10 is adapted to be removably applied to the mouthpiece of a telephone, speaking tube, or other device usually provided with a mouth for speaking purposes.

The object of this invention is to provide 15 an individual germ proof protector of this character which will safeguard persons using the telephone against infection and which is of simple and inexpensive construction and capable of being readily attached to and 20 removed from such mouthpieces, so that each person can conveniently use a fresh protector on the mouthpiece of the telephone prior to using the same and then discard the same.

25 In the accompanying drawings: Figure 1 is a fragmentary sectional elevation of a telephone showing the mouthpiece thereof equipped with one form of protector constructed in accordance with my invention. Fig. 2 is a front elevation of the same. Fig. 3 30 is a fragmentary sectional elevation of a telephone showing its mouthpiece equipped with another form of protector which embodies my improvements. Fig. 4 is a front elevation of the same. Fig. 5 is a fragmentary section, on an enlarged scale, showing the means for fastening the protector to the mouthpiece.

Similar characters of reference indicate 40 corresponding parts throughout the several views.

My improved protector is more particularly designed for use on a mouthpiece 1 which is of tubular form and tapers rearwardly in the shape of a bell, the front end 45 of this mouthpiece being open and adapted to receive the lips of a speaker while the rear end thereof communicates with the parts which are adapted to receive the tone. In the particular installation shown in the 50 drawings this mouthpiece forms part of a telephone and for this purpose the rear end thereof is mounted on the front wall 2 of the transmitter which latter may be of any 55 suitable or well known construction. It is

to be understood, however, that the use of my improved protector is not confined to this particular type of mouthpiece nor to telephone mouthpieces but may be used in connection with other forms of mouthpieces 60 and in connection with other analogous devices.

In its general organization the protector which contains my invention comprises a body 3 and a fastening device for attaching 65 this body removably to the mouthpiece. In the form shown in Figs. 1 and 2 the body of the protector is constructed generally in the form of a tube which tapers rearwardly and is adapted to be inserted into the bore 70 of the mouthpiece so as to form a lining therefor. At its rear end this body is provided with a transverse diaphragm 4 so that the body and diaphragm together form a complete screen across the passageway in 75 the mouthpiece.

At its front edge the body of the protector is provided with a resilient attaching rim whereby the same may be detachably connected with the front part of the mouthpiece which rim surrounds the peripheral part of the mouthpiece adjacent to the front end thereof. In its preferred form this attaching line comprises an inner annular flange or section 5 which projects rearwardly from the front edge of the body around the outer side thereof and an outer annular flange or section 6 projecting forwardly from the rear edge of the inner flange and surrounding the latter. The inner flange is of rearwardly reduced or tapering form and separated from the adjacent peripheral part of the body by means of an annular conical channel which opens rearwardly, and the outer flange is also of 95 rearwardly tapering form so that the same enlarges forwardly and is separated by an annular channel which opens forwardly, the diameter of the front edge of the last mentioned flange being greater than the diameter 100 of the front edges of the body and the inner flange connecting therewith. The rear or inner side of the meeting parts of the inner and outer flanges are constructed to form a forwardly tapering guide surface 7 the extreme diameters of which are respectively 105 larger and greater than the front edge of the mouthpiece of the telephone or other device.

When it is desired to apply this pro- 110

tector to the mouthpiece of a telephone or the like preparatory to using the same the body of the protector is inserted into the mouthpiece and the rim thereof is pushed 5 rearwardly against the front edge of the mouthpiece whereby the forwardly tapering bearing surface 7 of the rim is caused to engage the mouthpiece and spread or dis-tend the rim sufficiently to permit the inner 10 flange thereof to pass over the enlarged front end of the mouthpiece. After this inner flange has passed rearwardly beyond the enlarged front edge of the mouthpiece the rim again contracts and its inner flange 15 is caused to grip the peripheral portion of the mouthpiece immediately in rear of its front edge where the mouthpiece is of the largest diameter. This expansion and contraction of the rim for this purpose is ob-20 tained by constructing the protector of resilient material. As shown in Figs. 1 and 2, the protector is constructed of gauze or woven fabric which is sufficiently stiff to hold its shape after the same has been 25 formed, while in the construction shown in Figs. 3, 4 and 5 the protector is made of thin paper or similar material. In either of these forms the protector will completely cover those surfaces of the mouthpiece 30 with which the lips of the speaker are liable to come in contact when using the telephone and thus prevent infection or contraction of disease in the event that any disease germs have been deposited in the mouthpiece by a 35 prior user of the telephone. This protector does not interfere with the free transmission of speech through the telephone inasmuch as the effect of the sound waves pass freely through the protector if the same is 40 made of gauze, as shown in Figs. 1 and 2, and also transmits the vibrations to the telephone in case the protector is made of thin paper or similar material, as shown in Figs. 3, 4 and 5. If somewhat thicker material is 45 used the passage of the sound waves through the protector to the telephone may be facilitated by providing the diaphragm of the protector with a plurality of fine perforations 8, as shown in Figs. 3 and 4. If 50 desired, the gauze protector, shown in Figs. 1 and 2 or the paper protector shown in Figs. 3, 4 and 5 may be medicated or treated in any suitable manner by means of an anti-septic or germicide so as to further aid in 55 preventing the dissemination of a disease through the use of the telephone. An individual germ proof protector is thus pro-60 vided which is inexpensive and permits of a more sanitary use of a telephone. After 65 the user of the telephone has completed the conversation the protector may be slipped off from the mouthpiece and thrown away leaving the telephone free to be used in any desired manner by the following speaker.

65 Protectors of this character may be con-

veniently carried in a compact form by par-ticular or discriminating persons who de-sire to avail themselves of this means of safeguarding their health and the same may also be conveniently stacked in tiers in coin-operated vending machines suitably in-stalled adjacent to telephones so that the public may purchase or obtain the same otherwise for individual use in connection with a telephone or the like. By reversely 70 folding or bending the flanges or sections of the attaching rim in the manner described it is possible not only to easily push the pro-tector on to the mouthpiece of the telephone and also readily remove the same, but this construction of the rim also permits of very 75 compactly stacking these protectors so that a comparatively large number of the same may be stowed away in a comparatively 80 small space, this being particularly impor-tant for transporting the same and also for 85 stacking the largest number possible within a given space available in a coin controlled vending machine.

Owing to the simplicity of the construc-tion of this protector the same can be pro-90 duced at comparatively small cost so as to make it possible for the same to go into gen-eral use and thus promote the general 95 health of the community.

I claim as my invention:

1. A protector for mouthpieces comprising a tubular body, a diaphragm arranged transversely at the rear end of the body, and a reversed attaching rim arranged on the outer side of said body and consisting of an inner annular flange which projects rearwardly from the front edge of the body and is of rearwardly tapering form and an outer annular flange which projects for-100 wardly from the rear edge of said inner flange and is of rearwardly tapering form.

2. A protector for mouthpieces comprising a tubular body, a diaphragm arranged transversely at the rear end of the body, and a reversed attaching rim arranged on the outer side of said body and consisting of an inner annular flange which projects rear-105 wardly from the front edge of the body and is of rearwardly tapering form and an outer annular flange which projects forwardly from the rear edge of said inner flange and is of rearwardly tapering form and has its front edge of larger diameter than that of the front edge of said body.

3. A protector for mouthpieces comprising a body, and a resilient attaching rim ar-ranged around said body and having an in-110 ner flange which projects rearwardly from the body and is reduced and an outer flange which projects forwardly from said inner flange and is enlarged forwardly.

4. A protector for mouthpieces comprising a body, and a resilient attaching rim ar-ranged around said body and having an 115

inner flange which projects rearwardly from the body and is reduced and an outer flange which projects forwardly from said inner flange and is enlarged forwardly, the 5 rear side of the meeting parts of said inner and outer flanges being constructed to form a forwardly tapering surface for engaging

the front edge of a mouthpiece and cause the rim to be sprung outwardly and the inner side of said inner flange to grip the periphery of the mouthpiece in rear of its front end. 10

MARY GRIFFIN HEBERLY.
